UNITED STATES PATENT OFFICE.

JAMES A. CHARTER, OF CHICAGO, ILLINOIS.

EXPLOSIVE-ENGINE.

1,106,782.

Specification of Letters Patent. Patented Aug. 11, 1914.

Application filed November 15, 1913. Serial No. 801,111.

To all whom it may concern:

Be it known that I, JAMES A. CHARTER, a citizen of the United States, residing at Chicago, in the county of Cook and State of Illinois, have invented a certain new and useful Improvement in Explosive-Engines, of which the following is a specification.

This invention relates to that class of explosive engines in which a rotary sleeve or cylindrical valve is used in a cylindrical recess formed between an inner and an outer cylinder, the sleeve valve being driven by suitable mechanism.

The object of the invention is to provide a device of this class which is exceptionally simple, accessible, readily assembled and disassembled and inexpensive to build, which is efficient in operation and not readily liable to get out of order.

20 The invention is an improved form of the device shown, described and claimed in my prior patent application, Serial Number 713,766, filed August 7, 1912.

25 The invention consists in a structure in which the inner of said two cylinders is detachably supported at both ends against sidewise movement, thereby doing away with unnecessary friction and strain upon the valve; in the use of means at one end of 30 the inner cylinder for supporting it upon the outer cylinder and in so supporting the other end of said cylinder as to allow for its lengthwise expansion with reference to the outer cylinder.

35 The invention further consists in simultaneously guiding the inner end of the inner cylinder from the outer cylinder preferably by a loose ring which is accurately fitted and supported so as to maintain the 40 inner cylinder in proper position with reference to the outer cylinder while permitting lengthwise expansion of the cylinder.

The invention further consists in making 45 the sleeve valve in two parts, one containing gearing located preferably near the inner end of the cylinder while the other portion of the sleeve is detachable therefrom for the purpose of repair without its being necessary to remove that portion of the sleeve 50 carrying the gears.

The invention further consists in providing the gearing upon the aforesaid portion of the sleeve with parallel bearings on opposite sides of the gear so as to cause the

same to travel very steadily and with as little friction as possible.

The invention further consists in details hereafter pointed out in the specification and claims.

Referring to the drawings in which similar numerals indicate the same parts throughout the several views, Figure 1 is a vertical sectional detail view through an engine cylinder equipped with this invention in its preferred form, taken on the line 1—1, 60 Fig. 2. Fig. 2 is a side view of a four cylinder engine equipped with the device of this invention, the case being partially broken away so as to show the interior of two different cylinders. Fig. 3 is a plan view 70 taken on the irregular line 3—3 of Fig. 2, showing the arrangement of the ports and passages for fuel material leading to the cylinders and for the exhaust therefrom.

The device, of course, has to be supported 75 and in the particular case here illustrated the crank case 10 is used for the purpose, the same being closed at its bottom with the oil pan 11 of conventional construction. Rising from the base or crank case 10 and secured thereto in any suitable manner is an outer cylinder 12 provided with a water space 14 in the ordinary manner. Closing the upper end of this outer cylinder 12 is a flat head 16 also preferably containing a 80 water space 18 communicating through the passageway 20 with the water space 14 heretofore described. Rigidly secured to this head 16 is an inner cylinder 22 extending down inside the outer cylinder 12 to and 85 through the upper end 24 of the base 10, the inner end 26 of said inner cylinder 22 fitting into the ring so loosely that there is no question at all about the inner cylinder 90 being able to expand freely lengthwise through the upper plate 24 of the base 10, thus taking care of all expansion of the inner cylinder when under working conditions.

It will be noticed that a collar 30 preferably of hardened steel is provided just above the upper plate 24 preferably but not necessarily let into it as shown and that said collar has a bearing at 31 upon the outer cylinder 12. This collar 30 is preferably quite 100 accurately made so as to maintain the inner cylinder 22 in centered position with reference to the outer cylinder while allowing for

the expansion of the inner cylinder above referred to. The upper end of the inner cylinder 22 also closely fits and contacts the outer cylinder at 33 for a short distance, thereby insuring the accurate centering of the inner cylinder with reference to the outer cylinder at this point. The inner cylinder is, except at the points noted, of sufficiently smaller diameter than the outer cylinder to provide an annular recess between the inner and outer cylinders for the insertion and rotation of the cylindrical sleeve valve 32. This valve is, as shown, made in two parts 32 and 32^a joined together by a clutch joint 34 so as to prevent rotation of either part of the valve independent of the other while permitting the removal of the upper portion 32 of the valve from the portion 32^a whenever the operator has first taken hold of the plate 16 and lifted it and consequently the inner cylinder 22 upward as shown in Fig. 1 leaving the upper valve member 32 exposed so that it may be removed.

The lower valve member 32^a carries a toothed section 36 which has bearing at its bottom in the ring 30 heretofore described and at its top another ring 38 of hardened steel. This ring 38 is provided with a flange 40 which closely fits the projecting end 42 of the outer cylinder so that the lower valve member 32^a has an accurately adjusted bearing upon these two rings 30 and 38 and, therefore, in practice does not depend upon the inner cylinder for guidance or support, there being in practice a film of oil between the inner cylinder 22 and the lower valve member 32^a. This lower valve member 32^a is driven by a worm 44 on a shaft 46, the teeth of the worm meshing with the teeth 36 on the circumference of the valve member 32^a. This worm is carried inside an enlarged portion of the case or outer cylinder as shown and as is fully described and claimed in my said prior application. The shaft 46 is suitably journaled by means not shown and carries a sprocket wheel 48 over which travels a sprocket chain 50 which in turn travels over a sprocket wheel 52 on the main shaft 54 of the engine. This shaft 54 in the interior of the case is a crank shaft having a plurality of crank pins 56 of ordinary construction one for each cylinder of the engine and on each crank pin is a connecting rod 58 suitably attached to a piston 60 inside the inner cylinder 22. In order to make the device an operative one, each of the cylinders of the engine is provided with suitable intake ports 62 and exhaust ports 64 forming no part of this invention. Other forms of minimum friction or frictionless bearings may be substituted at the points of contact between the valve member 32^a and rings 30 and 38 without departing from this invention.

It will be noticed that the ring 30 is of larger diameter than the ring 38 so that whenever the base 10 is removed from the parts above it, both rings and the lower valve member 32^a may all be removed through the lower end of the outer cylinder. It will also be noticed that the inner cylinder is suspended and carried by the flat head 16 from the outer cylinder as in my said prior application and that the head and cylinder may be removed together without disturbing the other parts, thereby making the upper portion of the sleeve removable.

I claim:

1. In a device of the class described, a base, an outer cylinder on said base, an inner cylinder smaller than the outer cylinder removably insertible through the outer cylinder while it is in place on the base and into a suitable opening in the base with whose wall it has sliding engagement to allow for expansion and contraction of said inner cylinder while supporting the inner cylinder against lateral movement.

2. In a device of the class described, a base, an outer cylinder, means for detachably securing the outer cylinder to the base, an inner cylinder smaller than the outer cylinder removably insertible through the outer cylinder while it is in place on the base and into a suitable opening in the base with whose wall it has sliding engagement to allow for expansion and contraction of said inner cylinder while supporting said inner cylinder against lateral movement.

3. In a device of the class described, a base, an outer cylinder on said base, an inner cylinder smaller than the outer cylinder removably insertible through the outer cylinder while it is in place on the base and into a suitable opening in the base with whose wall it has sliding engagement to allow for expansion and contraction of said inner cylinder while supporting the inner cylinder against lateral movement, and means for detachably securing the outer ends of the two cylinders together, said securing means being so constructed as to rigidly space said cylinders apart at this point to permit the proper operation of a cylindrical valve placed in a space formed between them.

4. In a device of the class described, a base, an outer cylinder, means for detachably securing the outer cylinder to the base, an inner cylinder smaller than the outer cylinder removably insertible through the outer cylinder while it is in place on the base and into a suitable opening in the base with whose wall it has sliding engagement to allow for expansion and contraction of said inner cylinder while supporting said inner cylinder against lateral movement, and means for detachably securing the outer ends of the two cylinders together, said securing

means being so constructed as to rigidly space said cylinders apart at this point to permit the proper operation of a cylindrical valve placed in a space formed between them.

5. In a device of the class described, a base, two concentric cylinders carried by the base, the inner of said cylinders carrying at its outer end a flanged head at right angles 10 to its axis fitting over and detachably secured to the outer cylinder and having its inner end extending slidably through an opening in the base to allow for the expansion and contraction of the inner cylinder, a 15 valve member rotatable between said cylinders when in the position named and means for rotating the valve.

6. In a device of the class described, two concentric cylinders spaced apart to receive 20 a valve member between them, the bore of the outer cylinder being such that both the valve member and inner cylinder may be freely withdrawn from one end of the outer cylinder, a shoulder at one end of the inner cylinder spacing it from the outer cylinder to maintain said valve space, a detachable 25 spacing member insertible between the opposite ends of the cylinders for the same purpose, and means for securing the parts to 30 assembled position.

7. A device of the class described, including two concentric cylinders of different sizes to form a space between them, a valve member in the space between them and a 35 separate ring space member insertible between the adjacent walls of the two cylinders spacing them apart to maintain the valve space constant.

8. A device of the class described includ- 40 ing an outer cylinder, an inner cylinder re-

movably insertible inside the outer cylinder smaller than the outer cylinder so as to provide an annular space between them for the insertion of a valve member, means spacing the inner ends of the two cylinders, a member 45 projecting radially from the outer end of the inner cylinder into contact with the interior circumference of the outer cylinder to accurately center the inner cylinder with reference to the outer cylinder at that point, 50 and means for detachably securing the parts in assembled position, the result being that the inner cylinder may first be removed leaving the valve member freely removable 55 from the outer cylinder.

9. A device of the class described, including an outer cylinder, an inner cylinder smaller than the outer cylinder so as to form an annular space between them, inserted through said outer cylinder, a member 60 spacing the inner ends of the two cylinders, a cylindrical valve member rotatable in the annular space formed between the cylinders, said valve member being made in two parts 65 detachably coupled together, one of said portions of the valve member being provided with driving means, and means operating upon said driving means for driving said valve member, the whole so arranged that the portion of the valve member which does 70 not contain the driving means may be removed without disturbing the other portion.

In witness whereof, I have hereunto subscribed my name in the presence of two witnesses.

JAMES A. CHARTER.
